Affis.

UNITED STATES PATENT OFFICE.

WILLIAM F. REACH, OF CHICOPEE, MASSACHUSETTS, ASSIGNOR TO A. G. SPALDING & BROS., OF JERSEY CITY, NEW JERSEY, A CORPORATION OF NEW JERSEY.

SKEE-HARNESS.

1,322,820.

Specification of Letters Patent. Patented Nov. 25, 1919.

Application filed July 10, 1918, Serial No. 244,276. Renewed April 2, 1919. Serial No. 287,075.

To all whom it may concern:

Be it known that I, WILLIAM F. REACH, a citizen of the United States, and resident of Chicopee, Massachusetts, have invented certain new and useful Improvements in Skee-Harness, of which the following is a specification.

The invention consists of the features and combination of parts hereinafter described and particularly pointed out in the claims.

In the drawings:

Figure 1 is a plan view of the harness.

Fig. 2 is a longitudinal elevation.

Fig. 3 is an end elevation, with the skee 15 in section.

Fig. 4 is a detail bottom plan view of the forward portion of the harness, and,

Fig. 5 is a similar view of a modification.

In the drawing 1 is a plate having down-turned sides 2 with ears 3 having openings 4 to receive bolts or pins for securing the plate to the skee, the down-turned sides being spaced apart a proper distance to embrace the skee between them. This plate 25 has a forward extension 5 lying in a plane above the plane of the top of the main part thereof. To this forward extension the toe clamps 6 are adjustably attached by bolts 7 passing through the slots 8, which extend 30 in a direction transversely of the extension, said slots being in line with each other. The toe clamps are formed from pieces of flat metal having their forwardly extending arms 6' mounted on the bolts and clamped 35 by the heads of the bolts bearing against their under sides and pressing them up against the underside of the elevated extension of the main plate. The clamps are guided through slots 9 in the sides of the 40 main plate and their upturned ends are arranged at an inclination to the longitudinal axis of the harness and are convergent toward the front to suit the shape of the foot and their upper ends are slightly inturned.

In adjusting the clamps the nuts 10, which clamp the bolts in place, are loosened and the clamps are shifted laterally to the desired positions and the bolts are then tightened up.

It will be observed that by the use of the forward extension of the main plate and the angular form of the clamps with their arms extending forward the points at which the said clamps are adjustably secured are

at the extreme front of the harness plate extension and at a point well in advance of the clamping wings 6, and well in advance of the point where the ball of the shoe bears. These means of adjustment are thus readily accessible instead of being borne upon or covered by the shoe and it is not necessary to remove the foot in order to adjust the clamps, but on the contrary the user may keep his foot in place and quickly and accurately adjust the clamps thereto, and furthermore the wearer will not suffer discomfort by reason of resting on the projecting nuts of the bolts.

The forwardly extending clamp arms are bent intermediate of their length at 11 and the shoulders thus afforded are adjacent the shoulder of the plate at 12.

The strain on the clamps tending to press them apart is resisted in part by the wall of the slots through which they pass and this tendency of the clamp to turn about the bolts as a pivot point is overcome and the shoulders just mentioned can contribute to this end.

Heavy webbing shown at 13 is riveted to the main plate at a point just in rear of the shoulder afforded by the elevated front extension of the plate, this webbing from this point extending loosely over the plate, and in rear thereof to a point under the instep, where it terminates and is provided with a cross piece 14 consisting of a metal piece of channel form embracing the end of the webbing and riveted thereto at 15. The ends of this cross piece project laterally beyond the side edges of the webbing and are provided with notches 16 to receive the heel fastening. This consists of a strap to pass around the heel to hold the foot forward in place between the clamps. One end of the strap may be permanently held in place by a part of the buckle 17 engaging one of the notches which may be closed sufficiently to hold the buckle by pressing the extreme end of the cross piece inwardly toward the longitudinal axis of the harness to grip the buckle and retain it.

The other end of the strap is provided with a toggle arrangement detachably connected with the cross piece. This toggle clamp includes a link 18 to removably engage the notch in the cross bar, a lever 19 pivotally connected at a point 20 interme-

diate of its ends to said link, and a link 21 pivoted to the end of the straining lever, and connected with the end of the heel strap. The strap can be adjusted as to 5 length by the buckle 17 and having been placed in position around the back of the foot and the link 18 engaged with the cross bar it is only necessary for the user to throw the handle of the straining lever rear- 10 wardly to tighten the strap and thus hold the foot to the harness.

The straining lever when thus turned throws the pivot point of the links out of line, so that the greater the strain the 15 tighter the lever will be held in locked position.

In removing the harness the straining lever is thrown forwardly and the increased 20 length afforded by thus throwing the links wide apart is sufficient to allow the link 18 to be readily slipped out of the notch in the cross piece, and the back strap does not have to be dragged off from the back of the foot, but gives a free release thereto.

25 Instead of employing a separate bolt for each clamp I may employ the construction shown in Fig. 5 in which both of the forwardly extending arms of the clamps are held by a single bolt 22, a slot 23 extending 30 in the longitudinal direction of the harness.

This means of adjustment, like that first described, is carried on a forward extension of the main plate, where it is removed from under the ball of the foot and is in position 35 to be readily accessible, while the foot is in place between the clamps.

The clamps are provided with slots at 24 to receive a toe strap.

40 The flexible webbing and the strap attached to the rear terminal of the same forms a holding means for the foot which allows lateral play of the ankle and prevents twisting of the ankle in the case of accidents or falls. The arrangement of the 45 clamps under the plate leaves the upper side free for the placing thereon and attachment thereto of the webbing.

It will be seen that the back strap is in 50 the same horizontal plane with the webbing. As shown in Fig. 2, the back strap has its center line directly in line with the center line of the webbing and when the parts are strained there is no tendency to tip the connection by the pull from the back strap which is directly in line with the center of the thickness of the webbing.

55 What I claim is:

1. A skee harness comprising a front 60 plate, with means for attaching the same to the skee, clamping members movably mounted on the plate and having arms extending forward from the clamping points, means at the forward ends of the said arms for adjustably securing the same to the plate, 65 and a guiding connection between the plate

and said members by which the rear portions of said members are slidably on the plate, substantially as described.

2. A skee harness comprising a front plate having down turned slotted sides, 70 with means for attaching the same to the skee, clamping members movably mounted on the plate, and having arms extending forward from the clamping points and means at the forward ends of the said arms 75 for adjustably securing the same to the plate, said forwardly extending arms underlying the said plate, said clamp members having their rear portions extending laterally through the slots of the downturned 80 sides, substantially as described.

3. A skee harness comprising a front plate having downturned slotted sides, with means for attaching the plate to the skee, clamping members movably mounted on the 85 plate and through said slots, and having arms extending forward from the clamping points and means at the forward ends of the said arms for adjustably securing the same to the plate, said arms underlying the 90 plate, and webbing overlying the plate and attached thereto, substantially as described.

4. A skee harness consisting of a plate having downturned sides with slots therein, and with means for securing the plate to the 95 skee, said plate having a forward extension raised above the plane of the main body of the plate, clamps guided through the slots of the plate's sides, and having arms extending forwardly beneath the plate and its extension and having their forward ends elevated to lie close to the underside of the extension and means for adjustably connecting the front ends of the clamp arms with the forward extension of the plate, substan- 100 tially as described.

5. A skee harness comprising a front plate, a strap to pass around the heel, a permanent but adjustable connection for one end of the strap, a detachable connection for the other end of the strap comprising a member to hook into place and a toggle lever connected to said member to take up the slack in the strap, substantially as 110 described.

6. A skee harness comprising a front plate, clamping means, a flexible connection secured to the plate, a channeled cross bar embracing and secured to the flexible connection, said cross bar having a notch 120 at one end and a strap attached to the other end of the bar and having means to removably engage the notch substantially as described.

7. A skee harness comprising a flexible 125 member connected at its forward end to the skee, a cross bar of channel shape in cross section embracing and secured to the rear end of the flexible member and arranged with the center of its height in line with 130

the center of the flexible member, and a strap detachably connected to the end of the cross bar and adapted to pass around the back of the heel, substantially as described.

8. A skee harness comprising a flexible member connected at its forward part to the skee, a cross bar attached to the rear end of the flexible member and having a hook 10 at one end and a strap attached to one end of the cross bar and having its other end detachably connected with the hook, substantially as described.

9. A skee harness comprising a flexible member, connected at its forward part to the skee, a channeled cross bar attached to 15 the rear edge of the flexible member and

having a projecting end with an open notch in its forward edge, a strap having means connecting with the other notched end of 20 the cross bar and permanently retained in said notch, and means for detachably connecting the free end of the strap with the open notched end of the cross bar, substantially as described.

10. A skee harness comprising a flexible member attachable at its front end to the skee and a back strap attached to the flexible member and arranged with the center of its height in line with the center of the thickness of the flexible member.

In testimony whereof, I affix my signature.

WILLIAM F. REACH.
